UNITED STATES PATENT OFFICE

JOHN KARMAZIN, OF DETROIT, MICHIGAN

RADIATOR CONSTRUCTION

Application filed May 28, 1927. Serial No. 194,899.

This invention relates to radiators, condensers and the like, and particularly to radiators of the fin and tube type in which the fluid conducting tubes are formed by the nesting of tapering tube sections carried by and extending transversely from superposable fin elements. Such a radiator is disclosed in my prior copending application, Ser. No. 641,850.

It is an object of the present invention to provide an improved means for securing a fluid tight joint between successive tube sections in a radiator of the type above mentioned.

A further object of the invention is to provide a solder receiving space between parts of the nesting tube sections while maintaining close contact between other adjacent parts.

A further object of the invention is to provide tube sections comprising varying degrees of taper, and to utilize the varying taper in securing fluid tight joints between successive tubes and to increase the strength of the radiator.

A further object of the invention is to so construct the nesting tubes that a recess of wedge shaped cross section is provided between successive tubes for the reception of a sealing medium.

With these and other objects in view my invention consists in the novel devices, combinations and arrangements of parts which are illustrated in the drawing, and will be hereinafter more fully described.

In the drawing:

Fig. 1 is a fragmentary front elevation of a radiator of a type to which the present invention is applicable.

Fig. 2 is a fragmentary sectional elevation of a tube embodying one form of the present invention.

Fig. 3 is a fragmentary sectional elevation of a tube embodying another form of the invention.

The radiator consists of a number of similar elements, each comprising a fin 5, from which extends transversely one or more tubular projections denoted generally by the numeral 6. Preferably each fin 5 is provided with a number of projections 6, and the pro-

jections of each fin are adapted to nest within the projections of the next lower fin to form continuous tubes which are provided at their ends with suitable outlets or connecting devices, all as more fully explained in my prior copending application above identified.

The present invention contemplates a novel and effective means of securing fluid tight joints between the successive tube sections. To this end the sections are so formed that when nested together a part only of the overlapping walls are in contact, one or more annular tapering recesses being provided between the remaining overlapping sections, for the reception of a sealing medium such as solder.

Various constructions may be used for this purpose. In the embodiment of the invention illustrated in Fig. 2, for example, each tube section comprises two distinct parts 7 and 8 having different angles of taper. The part 7 adjacent to the fin 5 tapers more than the end portion 8. Thus when the sections are nested together a portion of the slightly tapering end section 8 of the inner section lies adjacent the more sharply tapering part 7 of the outer section, leaving an annular wedge shaped recess between them. The recesses thus formed are filled with an adhesive sealing medium 9, such as solder.

In the form of the invention illustrated in Fig. 3, the tube sections 6 do not comprise two distinct parts having different angles of taper, but each cross section of the tube walls forms a continuous arc, the taper of the tube thus gradually decreasing from the fin 5 toward the end of the tube. Obviously when such tubes are nested together their walls contact only for a limited distance near the end of the inner tube, and a space which increases in width toward the fins 5 remains between a part of the overlapping portions of their walls, which space may be filled with solder or other sealing medium 9a.

To facilitate transverse circulation of the fluid within the tubes as well as to secure additional solder space, the extreme tips of the tube sections may be turned inward slightly, as illustrated at 10 in Fig. 2, and the space thus provided between the turned tip 10

and the wall of the adjacent tube section may be filled with solder 11, providing a second wedge shaped solder seal between the walls of adjacent tubes.

- 6 Means for positively securing the parts of a sectional tube together with fluid tight joints is thus simply and cheaply provided. The provision of the solder containing recess, moreover, permits of wider limits of accuracy 10 in the manufacture of the tubes, thus decreasing both the tool cost and the number of rejections on account of inaccuracies in size. The production of assembled radiator cooling sections is thus facilitated and cheapened.
- 15 The specific embodiments of the invention which are shown in the drawing and have been described in detail are to be regarded as illustrative rather than restrictive, the invention being readily susceptible of other 20 embodiments all falling within the scope of the appended claims.

What I claim as my invention is:

- 25 1. An element for a sectional tubular radiator comprising a fin element having tapering tubular projections extending therefrom, each projection comprising sections with different degrees of taper, the walls of said sections meeting in an angle, and the ends of the projections being turned inward.
- 30 2. A radiator cooling section comprising a plurality of superposed fin elements having tubular projections extending transversely therefrom and nesting with the projections of the adjacent element, said tubular projections 35 having sections of substantially different degrees of taper in the nested portion to provide a plurality of annular spaces between the overlapping walls of the tube sections, and solder in said spaces uniting said projections 40 into a continuous tube.

In testimony whereof I have affixed my signature to this specification.

JOHN KARMAZIN.
